Attorney

UNITED STATES PATENT OFFICE.

FRED A. HOMEWOOD, OF GLENDO, WYOMING.

WHEEL TIGHTENER.

Application filed October 2, 1922. Serial No. 591,830.

To all whom it may concern:

Be it known that I, FRED A. HOMEWOOD, a citizen of the United States, residing at Glendo, in the county of Platte and State 5 of Wyoming, have invented certain new and useful Improvements in Wheel Tighteners, of which the following is a specification, reference being had to the accompanying drawings.

10 This invention relates to wheel adjustors and tighteners, and has for its object to provide a device of this character capable of permitting either the spokes or the felly of the wheel to be tightened.

15 It is another object of the invention to provide a jack of this character capable of being adjusted according to the size of the wheel before being applied, and wherein the jacking operation can be accomplished by 20 one movement of the lever of the device.

It is a further object of the invention to provide a device of this character having a base adapted to engage a portion of a wheel, and wherein the device is operative within 25 the wheel to move the pivots thereof to a dead center.

It is a still further object of the invention to provide a device of this character wherein the actuating member is provided 30 with means for adjusting its position relative to the dead center of the pivots.

With these and other objects in view, the invention consists in the improved construction and arrangement of parts to be herein- 35 after more particularly described, fully claimed and illustrated in the accompanying drawings, in which:—

Figure 1 is a fragmentary side elevation of a wheel showing the invention applied;

40 Figure 2 is a longitudinal sectional view of the tightener in its retracted position; and

Figure 3 is a fragmentary elevation of the 45 tightener in its extended position.

Referring to the drawings, 5 designates a saddle base member adapted to engage the felly of a wheel. Projecting from the base is a pair of ears 6 having bearing openings 7. Carried by one end portion of the upper face of the base 5 is a boss 8, the purpose of which will be hereinafter described.

50 An actuating lever 9 is provided, the end portion 10 of said lever being substantially offset with respect to the body portion of the lever and also enlarged, said enlarged portions having cam extensions 11 and 12.

The extension 11 is provided with an opening 13, and the extension 12 is provided with an opening 14. A pivot pin 15 is adapted to be passed through the opening 14 60 and the bearing openings 7 of the ears 6 to pivotally support the lever 9 upon the base 5. It is of course obvious that the body portion of the lever 9 may be made as long as desired. 65

In connection with the actuating lever, jack means are used, said jack means comprising a threaded shank 16, the end portion 17 of the shank being enlarged and offset, said enlargement being bifurcated as at 18 70 for the reception of the extension 11 of the lever. The arms of the bifurcation are provided with registering openings 19 adapted to receive a pivot pin 20, said pivot pin also passing through the opening 13 of the extension 11. When the jack shank 16 is applied to the lever, the offset portion is extended toward the lever so as to prevent contact of the threaded shank with the major portion of the lever in the operation of the 75 device. A tubular member 21 is provided, the end 22 of said member being closed and tapered as at 23, according to the divergent relation of the spokes at the hub of the wheel, so as to permit the end 22 to engage 80 the hub of the wheel without interfering with the position of the spokes. The end 24 of the sleeve is open, the inner wall of said end being threaded for a short distance 85 for the reception of the threaded shank 16. 90

The actuating lever 9 is provided with a threaded socket 25 adjacent the extension 12. This socket is intended to receive a screw 26 which is at times adapted to engage the boss 8. 95

In operation, the device is placed between the spokes of a wheel with the saddle base 5 resting upon the felly of the wheel. The sleeve 21 of the jacking means is adjusted by rotating the same on the shank 16. The 100 operating lever is then moved downwardly toward the base so as to swing the sleeve 21 toward and into engagement with the hub of the wheel. At the limit of the movement of the lever 9 the screw 26 will engage the 105 boss 8 so as to hold the pivots 15 and 20 substantially on a vertical dead center, so that movement of the jacking means away from the hub is impossible. By the provision of the screw 26 it is not possible for 110 the lever to move the pivots beyond the dead center when the device is being moved to ex-

tended position. Therefore, there is no danger of the dead center being accidentally broken so that the wheel may be held in its stretched position indefinitely. During this 5 period a suitable washer may be applied to the exposed portion of the tenon of the spoke and if necessary a wedge may also be inserted in the separated portions of the felly, thus properly tightening the wheel. 10 The lever 9 is then swung toward the jacking means so as to break the dead center of the pivots, whereupon the device may be easily removed from the wheel. From the foregoing it will be readily seen that this 15 invention provides a novel form of wheel tightener which requires only one movement of the lever in order to stretch the parts of the wheel to permit the insertion of washers or wedges. Regardless of the fact that only 20 one movement of the lever is necessary, it is possible to adjust the jacking means to accommodate any size of wheel and to also adjust the device to stretch the wheel various distances. All of these features are possessed by a compact device composed of 25 only a small number of simple parts which will not easily get out of order.

What is claimed is:—

1. A wheel tightener comprising a base 30 member adapted to be engaged against the inner periphery of a wheel felly and formed

with spaced ears, an elongated lever having a head formed with opposite extensions, one extension being received and pivoted between said ears, a rod having one end offset 35 and forked and pivotally engaged upon the other extension, a sleeve adjustably mounted upon said rod and adapted to be engaged against the wheel hub between the spokes thereof, and stop means for limiting swing- 40 ing movement of the lever whereby the second named pivot point will be maintained slightly beyond dead center with respect to the first named pivot point, said rod and sleeve being supported entirely by the lever. 45

2. In a device of the character described, a base adapted to be disposed against the inner periphery of a wheel felly and formed with ears, a lever having a head including opposite extensions, one extension being pivoted between said ears, an extensible hub engaging member pivotally connected with the other extension, a protuberance on the base, and a screw extending from one edge of the lever and engageable with said protuberance whereby to limit movement of the lever whereby the second named pivot will be maintained slightly beyond dead center 50 with respect to the first named pivot. 55

In testimony whereof I hereunto affix my 60 signature.

FRED A. HOMEWOOD.
